UNITED STATES PATENT OFFICE

FRANK J. WINDER, OF BRACKENRIDGE, PENNSYLVANIA, ASSIGNOR TO ALLEGHENY STEEL COMPANY, A CORPORATION OF PENNSYLVANIA

CONTINUOUS-HEATING FURNACE

Application filed March 1, 1928. Serial No. 258,253.

This invention relates to an improvement in furnaces and more particularly to a continuous heating furnace.

An object of this invention is to provide a furnace for heating sheet bars, slabs, billets and the like in a continuous manner and which will be especially adapted for heating slabs, billets, squares, rounds, etc., composed of metals requiring slow heating.

Another object of this invention is to provide a continuous heating furnace having a movable hearth for receiving the material to be treated and for conveying such material from one position to another in the furnace.

Another object of this invention is to provide a heating furnace having the above characteristics, means associated with the said furnace for removing the heated material therefrom and means associated with the movable hearth for raising, lowering and rotating the said hearth within the furnace.

Other objects will be made apparent throughout the further description of the furnace illustrated in the accompanying drawings and set forth in the appended claims.

In the single sheet of drawings, Fig. 1 is a top plan view of a furnace constructed in accordance with the invention having the top or roof removed and Fig. 2 is a vertical sectional view taken through the center of Fig. 1 having the top or roof in place.

The invention comprises in general a vertical furnace 11 cylindrical in shape having a removable top or roof 12 a movable grate 13, a plurality of sets of supports 14 and 15 vertically spaced apart, means 16 for raising and lowering the grate within the furnace, means 17 for rotating the furnace within the grate and a means 18 for forcing the treated material out of the furnace.

The furnace 11 may be constructed of any suitable refractory material such as fire brick and preferably lined with a refractory alloy 19 for preventing particles of the fire brick or the like from chipping off, due to expansion and contraction and falling in contact with the material being treated.

The grate 13 may be also constructed of any suitable refractory material such as fire

brick and is also preferably lined with the refractory alloy 19, which lining greatly increases the life thereof. A suitable seal 21, such as sand, is provided around the bottom of the hearth for sealing the hearth with the furnace. A slot or opening 22 is provided through the hearth adjacent one of its ends, the said opening 22 adapted to register with a chute 23 for permitting the material treated to pass out of the furnace. The grate is also provided with a suitable stop 24 extending upwardly adjacent the opening 22 for guiding the material into the slot and out the chute 23. Through the opposite side of the furnace from the chute 23, I provide a threaded means 18 for forcing the material along the grate 13 into contact with the stop 24 and out the opening 22.

The means 16 for raising and lowering the grate 13 within the furnace comprises a water cylinder 25 having a piston 26 disposed therein. The piston 26 is provided with a piston rod 27 extending upwardly and into engagement with the grate 13 and supporting the grate 13 in relative position with the piston 26. Any suitable means such as shown at 28 may be employed for connecting the piston rod 27 to the bottom of the grate 13. The piston rod 27 is also provided with a square or hexagonal portion 29 the purpose of which will hereinafter be described.

The furnace in general is supported by suitable pillars 31 disposed on a steel base 32 which is in turn supported by a concrete foundation 33. The hydraulic means 16 is conveniently disposed below the steel base 32 and within the concrete foundation 33.

The means 17 for rotating the grate 13 within the furnace comprises a motor 34 connected to the piston rod 27 by means of a suitable pinion 35 and gear 36. The gear 36 is provided with a square or hexagonal opening for receiving the square or hexagonal portion 29 of the piston rod 27. The gear 36 is turnably disposed upon the steel base 32 in any suitable manner such as shown at 37. The means 37 comprises corresponding grooves in the gear 36 and base 32 having suitable rollers associated therein.

The gear 36 and pinion 35 are provided

with a steel cover 38 for protecting the gear and pinion from dirt, moisture and the like and also for preventing the gear 36 from moving in an upward position.

5 It can be seen from the drawings, that as the piston 26 moves upward, the piston rod 27 is permitted to slide within the hexagonal opening in the gear 36 and by operating the motor 34 and turning the pinion 35 and gear 36, the piston rod 27 will rotate or turn with the gear.

In practicing the invention, the top 12 is removed from the furnace 11 by any suitable means such as a crane and the grate 13 is 15 raised within the furnace to the top thereof, at which time the material to be treated is superimposed upon the grate, each layer of the material being disposed at right angles to each adjacent layer, the widths of each 20 layer of material in each case being less than the distance between the oppositely disposed supports 14 and 15, the length of such layers being greater than the distance between either 25 of the said oppositely disposed supports 14 and 15.

In superimposing the material upon the grate, the grate may be lowered any desirable distance before superimposing the next layer and rotated 90° if desired.

30 The furnace may be heated by any suitable means such as gas burners 50, or the furnace may be constructed for using such fuel as coal, oil, or the like.

It will be obvious from the above that the 35 grate may be raised and lowered or rotated clockwise or counterclockwise any desirable number of times and any predetermined amount during the placing of the material to be treated within the furnace. In the 40 drawings 41, 42, 43 and 44 represent a plurality of layers or material to be treated, each layer being disposed at right angles to each adjacent layer. Since the supports 15 only 45 permit one layer to pass there-beneath in view of the manner in which the material is stacked, the single layer 44 may be brought below the supports 15 and turned to rest upon the supports 14. This provides space below, 50 above and around the entire layer 44 for the circulation of the heating gases and subjects the layer 44, which is the first layer to be 55 removed from the furnace to the proper temperatures, while the layers 41, 42 and 43 are undergoing a preliminary or pre-heating stage, the desirability of which will be obvious to those skilled in the art.

After the layer 44 has been subjected to the desired temperatures, the grate 13 is raised by the means 16 into contact with the layer 60 44, removing it from the supports 14 and rotating it 90° by the means 17 and lowered into the position, as shown at 44a, at which time the layers 44a may be forced out of the 65 openings 22 and the chute 23 and into a suitable receptacle, not shown.

Obviously the roof of the furnace may be removed and an additional layer placed therein after the lowermost layer has been removed from the furnace.

Briefly, one system of operation is as follows: The top 12 of the vertical chamber is removed, the hearth 13 is raised by means of its piston to the opening produced thereby, and cross stacked material to be treated is piled from this top through the opening upon the hearth 13. The piston of the hearth 13 is again operated, this time to lower the pile of material to be treated within the furnace chamber so as to allow placing of the material on a suitable support. The material is left 70 on the supports until any desired heating has been accomplished, then the hearth lifts the entire pile of material, removes the lowest layer thereof, and places the subsequent layer on the supports. New material can be placed 75 on this pile through the opening at the top of the furnace chamber as the lowermost layer is being removed.

In this furnace a continuous heating process can be accomplished. Material to be 80 treated enters the top, slowly progresses downwardly as a layer of a pile of cross stacked material and finally, when a desired heating has been accomplished, is removed 85 from the furnace. Simultaneously, with this removal, a new layer whose heating is to begin, may be introduced as the topmost layer 90 of the pile of material being treated.

While I have illustrated and described but one embodiment of this invention, it will be 95 apparent to those skilled in the art that certain changes, modifications, substitutions, additions, and omissions may be made in the structure and the method of operating the same without departing from the spirit and 100 scope of the appended claims.

What I claim as new and desire to secure by Letters Patent is:

1. In combination with a continuous heating furnace, a vertically disposed heating chamber, an imperforate removable top for 110 said chamber so that material may enter therethrough, means for supporting material being treated in said chamber, means extending upwardly through the bottom of said chamber for receiving material from the top portion of said chamber and being movable, for placing said material on said supporting means, and for removing a layer of said material from said supporting means when a 115 desired heat treatment thereof has been accomplished.

2. In combination with a continuous heating furnace, a vertically disposed closed heating chamber, an imperforate removable top for 120 said chamber so that material may enter therethrough, means for supporting material being treated in said chamber, means extending upwardly through the bottom of said chamber for receiving material from the top 125 130

portion of said chamber and being movable vertically and rotatably, for placing said material on said supporting means, for removing a layer of said material from said supporting means when a desired heat treatment thereof has been accomplished, for subsequently supporting said removed layer of hot material until taken from said furnace chamber and means for laterally removing the said layer.

3. In combination with a continuous heating furnace, a vertically disposed closed refractory heating chamber, an imperforate removable top for said chamber so that horizontal layers of edgewise disposed material may enter said chamber therethrough, means for supporting material being treated in said chamber, means extending upwardly through the bottom of said chamber for receiving material from the top portion thereof, for placing said material on said supporting means, for removing successively, at angles of 90° apart, each lowermost layer of said material from said supporting means when a desired heat treatment thereof has been accomplished, for subsequently supporting said removed layer of hot material until taken from said furnace chamber, and means extending through the wall of said chamber engaging one side of said layer and operating from the outside of said furnace to move said material edgewise for causing sheets at the opposite side of the same to fall vertically through a slotted discharge device.

In testimony whereof, I have hereunto subscribed my name this 24th day of February, 1928.

FRANK J. WINDER.
